UNITED STATES PATENT OFFICE.

ROBERT OTTO McMASTER, OF WHEELING, WEST VIRGINIA.

NASAL RESPIRATOR.

SPECIFICATION forming part of Letters Patent No. 369,019, dated August 30, 1887.

Application filed January 26, 1887. Serial No. 235,539. (No model.)

To all whom it may concern:

Be it known that I, ROBERT OTTO McMASTER, a resident of Wheeling, in the county of Ohio and State of West Virginia, have invented 5 certain new and useful Improvements in Nasal Respirators; and I do hereby declare that the following is a full, clear, and exact description of the invention, which will enable others skilled in the art to which it appertains to make 10 and use the same, reference being had to the accompanying drawings, and to letters of reference marked thereon, which form a part of this specification.

The object of my invention is to provide a 15 convenient and effective respirator for the nose, to prevent the inhalation of dust or poisonous chemicals calculated to injure the mucous membrane or lung-surface, and one that can also be used to advantage in the treatment 20 of asthma and hypertrophic catarrh in the manner of an inhaler.

My invention consists of a respirator adapted 25 to cover or incase the nose, made of caoutchouc, celluloid, or an equivalent material not liable to be injured by acids or other chemicals, 30 adapted to be secured to the nose by spring-clamps secured to the inside of the respirator, and which enter the nostrils one on each side of the center division, and expand the wings or side of the opening outwardly and clamp 35 them to the outer shell or wall of the respirator, and thus secure and hold the respirator in position.

In the drawings, Figure 1 shows the respirator 40 in position on the nose. Fig. 2 is a rear view of the respirator. Fig. 3 is a vertical central section, and Fig. 4 a horizontal or cross section.

The letter A designates the shell or case of 45 the respirator, adapted to inclose the nose and to conform to the contour of the face. In the lower portion of this case is a compartment, B, adapted to the receival of suitable filtering material or absorbent substances, such as sponge or cotton. This compartment is covered with a perforated plate or wire-gauze top, C, and has a hinged bottom plate, D, of similar construction, pivoted to lugs b b on the side of the case, and is secured in position by 50 a spring-catch, a. During respiration the air passes through this chamber in either direction.

E is the space intended for the receival of the nose. In this space are located two spring-clamps, F F', arranged parallel with the side 55 of the case and secured to the front portion at the center of the curve at e, leaving the side pieces free to be pressed inward, as indicated by dotted lines in Fig. 4.

Attached to the end of the spring-clamps, 50 and passing through openings in the side of the case, are projecting arms G G', having knobs attached for convenience in operating the springs.

c c are lugs on the ends of the springs, of 65 sufficient height to enter the nostrils and dis-tend or enlarge the same for the double purpose of assisting respiration and of securing the respirator to the nose by clamping the wings of the nose to the side of the respirator. 70

To secure the respirator on the nose, the springs are pressed inward by means of the projecting arms sufficient to permit the lugs on the ends of the springs to enter the nostrils, when the case is then placed over the nose and 75 pushed into position. Pressure is then removed, and the spring-clamps operate to hold the respirator in place. A similar operation will release the same.

The principal advantage of attaching the 80 respirator to the nose in the manner I have described is that it facilitates breathing by enlarging the nostrils, so as to enable the wearer to breathe entirely through the nose, and not have to use his mouth for breathing 85 purposes, and thereby require another respirator to cover the lower portion of the face.

Having described my invention, what I 90 claim, and desire to secure by Letters Patent of the United States, is—

The case A, having a compartment, B, provided with a hinged bottom, D, the top and bottom of said compartment being perforated, and spring-clamps F F', having lugs c c and outwardly-projecting arms G G', substantially 95 as and for the purpose set forth.

In testimony that I claim the foregoing as my own I hereby affix my signature in presence of two witnesses.

ROBERT OTTO McMASTER.
